CLAIM

The ornamental design for a distribution module, as shown and described.

DESCRIPTION

FIG. 1 is a front top quarter perspective of a distribution module showing the ornamental design of an embodiment; FIG. 2 is a rear bottom quarter view of the embodiment of FIG. 1;

FIG. 3 is a rear view of the embodiment of FIG. 1; FIG. 4 is a front view of the embodiment of FIG. 1; FIG. 5 is a first side view of the embodiment of FIG. 1; FIG. 6 is a second side view of the embodiment of FIG. 1; FIG. 7 is a top view of the embodiment of FIG. 1; and, FIG. 8 is a bottom view of the embodiment of FIG. 1. The broken lines in the drawing depict portions of the distribution module that form no part of the claimed design.

1 Claim, 7 Drawing Sheets
